UNITED STATES PATENT OFFICE

ANGEL ZUBERO AZCARAY, OF HABANA, CUBA

RAILWAY SWITCH

Application filed June 27, 1929, Serial No. 374,083, and in Cuba June 18, 1929.

This invention refers to rail-way switches, and has for its main object, the provision of a device of this kind, which may be operated from the train itself while traveling, said device being very simple, of easy operation, and avoiding the necessity and cost of a switchman.

Another advantage of this invention is to provide a railway switch of substantially automatic operation, the structure of which, besides offering complete safety in switching, is not susceptible, on account of its simplicity, to derangements, interruptions, or breakage.

15 In the drawings:—

Figure 1 is a top plan view, of a section of a railway, provided with a railway switch, object of the present invention.

Fig. 2 is a side elevation of a locomotive 20 equipped with an extra wheel to operate the switch, the object of the present invention.

Figure 3 is a top plan view, in detail, on an enlarged scale, and is a fragmentary view of the railway switch.

25 Figs. 4 and 5 are partial upper plan views, in detail, and on an enlarged scale, of the operative mechanisms of the railway switch upon the passage of the train or other rolling element.

30 Fig. 6 is a vertical cross section in detail, according to line 6—6 of Figure 3.

Fig. 7 is a vertical cross section, in detail, partial, according to line 7—7 of Figure 4.

Fig. 8 is a vertical cross section in partial detail, according to line 8—8 of Figure 5.

Fig. 9 is a vertical longitudinal partial section, in detail, according to line 9—9 of Figure 4, and

40 Fig. 10 is a vertical, longitudinal partial section, in detail, according to line 10—10 of Figure 5.

45 Referring to the figures of these drawings, in Figure 1, is shown a section of a railway, the rails of which are designated by 1 and 2, with a branch, the rails of which are designated by 2' (extension of the rail 2) and 3, said branch being connected to the main track by a switch 4, the points of which are secured to a narrow switch cross plate 5.

50 To the ties 10, of the track on both sides

of same, are fastened the ears 6 provided with bores, through which pass the rods 7 and 8, the rod 8 being divided into two sections 8 and 8' connected together by a Cardan union 11 so as to be extended along the outer rail of the branch track.

To the rods 7 and 8 next to the plate 5 are secured the hanging brackets 12 and 13, having slots 12' and 13' on their lower ends, through which are mounted the stems 14, 60 which bear on their ends a rocking cross-bar 15 placed under the plate 5 in a recess 15'' positioned between adjacent ties 10, and which bar is also provided with slots 15' which are slidably engaged with adjacent 65 stationary guide and support bars 16, suitably secured to the walls of the recess 15''. On the portions of said bar 15 above the slots 15', and on each side of said bar, are pivoted the latch fingers 17, each forced downward 70 through a leaf spring 18 and which latches engage the guide bars 16, when the bar 15 is rocked, and are thus placed on each end of the respective slot 15', said fingers being held in place by stops 19.

75 From the middle of the switch plate 5 depends an ear 20 and thereon is hinged by stem and slot connections an arm 21, the lower end of which is engaged by a like connection to the bar 15, this arm 21 being pivoted to a 80 bar 21' also fastened between the walls of the recess 15''.

To the rods 7 and 8, and to portions of the same in advance of the switch are secured as shown in the Figures 1, 5, 8 and 10, downwardly bent arms 22, the ends of which are engaged through slots 23', provided in the lower parts of corresponding blocks or operative elements 23 of the switch, said blocks being in turn provided on the upper ends with 85 heads 23''. The blocks are mounted for vertical movement in supports 24 provided with seats 24' for limiting downward movement of the normally elevated heads 23''. The supports are secured upon adjacent ties of 90 the track and to the sides of the rails 1 and 2. The lower parts of said block or operative piece 23 of the switch are housed in recesses 25 provided in the ground between 95 said two ties. In this connection it is to be 100

observed that when the switch is closed the engagement of the corresponding arms 22 with the blocks 23 is such as to normally maintain the heads in a slightly elevated position above the upper surfaces of the rails 1, 2.

Further along from the crossing, a portion of the rail of the main track 1 and the rail 2' of the branch, are cut, and movable blocks 26 are housed therein, and provided each with a head 26', which rests upon a suitable seat made in the same shape as the respective rail and having placed on one side of said block a protective plate 27 secured to the cut ends of each rail, by rivets, and on the opposite side, another plate 28 secured in like manner to the cut ends of the rails, and having a recess 28', the object of which will be explained further along.

The lower part of each block or operative piece 26, is housed in a recess 29 provided in the ground, between two of the ties 10 whereon the said rails bear and presents a slot 26" through which the loose end of an adjacent bent arm 30 is engaged. The arms 30 are secured to the rods 7 and 8 respectively, as shown in Figures 7 and 9.

The locomotives, or tractors of trains, or other rolling elements, constructed to run on rails provided with switches, similar to those which are the object of this invention, must be equipped, as shown in Figure 2, with a wheel 31 on each side, held by a frame 32, and operated by a hand wheel, and screw 33, against the stress of a spring 34, or else operated by any other mechanical arrangement desired, said wheel being placed in such a way as to be mountable during the travel of trains and on passing the crossing over the blocks or operative elements 23 and 26.

The operation of this switch is as explained in the following:

Assuming that a train is travelling over the track which is shown in Figure 1, and nearing the crossing fitted with the switch, which is also shown in same, the block 23 on the left is in a depressed position, under the action of the arm 22, as indicated by full lines in Figures 8 and 10. In such a position, the main track composed of the rails 1 and 2, will be open, and the branch line formed by the rails 2' and 3, closed.

If the travel of the train is along the main track, upon verifying that same is open, by the depressed position of the block 23 on the left side, we have only to take the main track, the train continuing in its forward route.

But if it be desired to follow along the branch track, instead of the main line, we have only to operate the hand wheel 33, on the right, upon arrival at the blocks 23, so that it engages the block at the right, and upon engaging the head 23" of same, for this purpose, it forces same downwardly, and thus the arm 22 will be moved downwardly,

giving a swift movement to the rod 8, and its section 8', which will drag the cross bar 15 with it, by its connection with the arm 13, which bar will slide over the guide rods 16. The guide rods 16 will be engaged by the latches 17, upon arrival at the end of the corresponding slot so that the bar 15, will then adopt the position shown in dotted lines in the Figure 6, and thereby causing the movement of the rod 7, due to its engagement therewith by the arm 12, the blocks 23 and 26 on the left thereby being in an abutting position, and the blocks 23 and 26 on the right in a depressed position, the switch plate 5, being driven, due to its engagement by the link 21 with the bar 15, and the switch 1, being in the position shown by dotted lines in Figure 1, and the branch track thereby opened, and the main line closed.

Now in this position, if a train is to have access to the main track, it will be only necessary to apply the operating wheel 31 on the left, which is applied upon the passage of the train over the abutting heads 23" and 26' of the blocks 23 and 26 on the left thereby operating the reverse movement of the bar 15 as seen in full lines in Fig. 6; the blocks 23 and 26 on the left, thereby will be in a depressed position, which is shown in Figures 9 and 10, and the blocks 23 and 26 on the right in an abutting position, which is seen in dotted lines in the same figures, and the main track open, as seen in full lines in Figure 1.

Having thus fully described the invention what is claimed as new and desired to be secured by Letters Patent is:—

1. A device of the character described including in combination, switch points, a cross bar connecting said points together, another bar mounted for sliding movement transversely of the points and positioned beneath the cross bar, a rockably mounted bar between the said first mentioned bars and having its ends loosely and operably connected thereto, selective train operable means operably connected with the ends of the slidably mounted bar for sliding said bar and for shifting said points, and latch means for holding the shifting bar in its set position.

2. A device of the character described including in combination, a main track and siding switch including points, a cross bar connecting the switch points together, rods arranged on opposite sides of the track and siding, depressible and train operable blocks operably mounted with respect to the track, sliding arms extending from the rods and operably connected with the blocks, other arms extending from the rods, a shiftable bar operably connected with the lower ends of the last mentioned rods and arranged beneath the lower ends of the cross bar, a rockably mounted bar having its ends operably connected to the shiftable bar and to the cross bar, said shiftable bar being provided with

slots, guide bars arranged through the slots, and spring controlled catches mounted on the shiftable bar above the slotted portions thereof for coacting with the guide bars to hold the shiftable bar in a set position.

5 In testimony whereof I affixed my signature hereto.

ANGEL ZUBERO AZCARAY.
